US00D997137S

(12) **United States Design Patent** (10) **Patent No.:** **US D997,137 S**
Kelley et al. (45) **Date of Patent:** **** Aug. 29, 2023**

(54) **SPEAKERPHONE**

(71) Applicant: **Plantronics, Inc.**, Santa Cruz, CA (US)

(72) Inventors: **John A. Kelley**, Santa Cruz, CA (US);
Nicholas W. Paterson, Aptos, CA (US);
Chase Patrick Bailey, Santa Cruz, CA
(US)

(73) Assignee: **Plantronics, Inc.**, Santa Cruz, CA (US)

(**) Term: **15 Years**

(21) Appl. No.: **29/729,449**

(22) Filed: **Mar. 26, 2020**

(51) **LOC (14) Cl.** **14-01**

(52) **U.S. Cl.** **D14/225**
USPC .....
